(57) **CLAIM**

The ornamental design for a microwave cooking tray, as shown and described herein.

DESCRIPTION

FIG. 1 is a top, isometric view of a microwave cooking tray in accordance with the present invention;
 FIG. 2 is a top view of the tray of FIG. 1;
 FIG. 3 is a bottom view of the tray of FIG. 1;
 FIG. 4 is a side view of the tray of FIG. 1, the opposite side view being identical; and,
 FIG. 5 is a front view of the tray of FIG. 1, the rear view being identical.
